ATTORNEY

UNITED STATES PATENT OFFICE.

HUBERT C. HART, OF UNIONVILLE, CONNECTICUT.

MATHEMATICAL INSTRUMENT.

1,320,689.

Specification of Letters Patent.

Patented Nov. 4, 1919.

Application filed May 13, 1919. Serial No. 296,906.

To all whom it may concern:

Be it known that I, HUBERT C. HART, a citizen of the United States, residing at Unionville, in the county of Hartford and State of Connecticut, have invented certain new and useful Improvements in Mathematical Instruments, of which the following is a specification.

This invention relates to what I shall consider as a mathematical instrument. I use this term, as will be inferred, more or less as a matter of convenience. The implement can obviously be employed with facility in several different arts. One of the primary purposes of the invention is the provision of an article of the kind set forth which can be inexpensively, easily and readily made, and which is capable of exercising several functions. For instance, on the one hand it might be used as a square, while on the other it may be utilized, after proper manipulation, as a rule.

In the drawings accompanying and forming part of the present specification, I have shown in detail one of the several forms of embodiment of the invention, which to enable those skilled in the art to practice the same will be set forth fully in the following description. I am not limited to this particular showing. I may depart therefrom in several respects within the scope of the invention defined by the claims following the said description.

Referring to the drawings:

Figure 1 is an elevation of an instrument involving the invention, in folded or collapsed condition.

Fig. 2 is an edge view of the same, as seen for instance from the right in Fig. 1.

Fig. 3 is a face view of the same, partially opened out.

Fig. 4 is a view of the instrument with the parts adjusted to produce a square.

Fig. 5 is a view of two of the sections in longitudinal alinement and with the third folded within one of the other sections.

Fig. 6 is a transverse section on the line 6—6 of Fig. 2, looking in the direction of the arrows.

Like characters refer to like parts throughout the several views which are on different scales.

As will be understood, the subject matter of the present case is really in the nature of a combination implement, although it should be stated at this point that this con-

dition may not always be present, because by virtue of one of the points of the invention, I may fold the article into a small compass, which is a consideration of some importance. When folded or knocked down, it can be easily carried in the pocket or in a tool box.

The device comprises as shown three sections as 2, 3 and 4, the sections 2 and 3 constituting in effect the body or main part of the implement, the section 4 presenting an auxiliary member. These sections 2, 3 and 4 may be made from any one of several different kinds of materials or of a composition of substances. They might be of metal or they might be of wood or of celluloid or anything else for that matter suitable for the purpose.

The sections 2 and 3 are as shown flexibly united as by a knuckle joint 5, at their inner ends. These sections 2 and 3 can be folded in superimposed or abutting relation as shown in Fig. 1 for example, or can be opened out into longitudinal alinement as shown by Fig. 5 or can occupy any one of a large number of intermediate positions, one of which is shown in Fig. 3. Each of them is channeled throughout its complete length, the ends of the respective channels being open except for the obstruction offered by the knuckle joint 5.

The section 4 is shown as pivoted as at 6, a pin or rivet being generally used for the purpose, between the side cheeks or flanges of the section 3, near the outer end thereof. This section 4 consists as shown of a somewhat elongated flat strip of rectangular form, its width being a little less than the combined width of the sections 2 and 3. The body section 2 is shown as having near its free end, the notch or slot 7 which can be easily produced by cutting away the bottom or outer wall of said section, a proper distance back from the front or free end thereof. The length of the slot 7 in fact is a trifle more than one-half the width of the section 4 for a reason that will hereinafter appear.

In Figs. 1 and 2 the instrument is shown as folded, the inner edge or edges of the sections 2 and 3 being in abutment throughout their complete length and jointly inclosing the section 4, which it will be remembered is jointed to the section 3. To open out the instrument, it is simply necessary to spread the sections 2 and 3 a distance suffi-

cient to permit the section 4 to be swung to right angles to the section 3, the relation it is shown as occupying in Fig. 4, at which time the inner squared end of said section 4 will 5 strike substantially against the bottom of the section 3. When this is done, the section 2 is swung down upon the section 3 and as it approaches such relation the section 4 is received within the notch or slot 7, thus 10 firmly holding the section 4 in a position at right angles to the superimposed or abutting sections 2 and 3 as illustrated by Fig. 4. This obviously produces a square. The sections 2 and 3, if desired, may be brought into 15 longitudinal coincidence as shown in Fig. 5, thus enabling them to jointly serve as a rule, this whether the section 4 be between the side flanges of the section 3 or not.

Desirably, the several sections are graduated. The graduations 8 on the sections 2 20 and 3 are of such character as shown, that collectively said sections 2 and 3 present a six inch rule. The graduations 9 on the section 3, however, do not measure completely 25 three inches, for as shown the auxiliary section 4 is a trifle shorter than either of the body sections 2 and 3, which as represented are of the same length.

What I claim is:

30 1. An instrument of the class described comprising two jointed main sections, an auxiliary section jointed to one of the main sections, the main sections being adapted to inclose the auxiliary section and one of the main sections having means to hold the auxiliary section at a predetermined angle to the main section which carries it.

40 2. An instrument of the class described comprising two channeled main sections jointed to each other and an auxiliary section jointed to one of the main sections, the

main sections being adapted to receive and jointly inclose the auxiliary section and one of the main sections having means to hold the auxiliary section at an angle to the main 45 section to which it is connected.

3. An instrument of the class described comprising two main sections jointed to each other, an auxiliary section jointed to one of the main sections, the main sections being 50 adapted together to inclose the auxiliary section, the auxiliary section being movable to an angle to the section which carries it, the other main section having a notch to receive the auxiliary section and the end of the notch 55 being adapted to hold the auxiliary section in its adjusted position.

4. An instrument of the class described comprising two main channeled sections jointed at their ends to each other, and an 60 auxiliary section jointed to one of the main sections near the outer end thereof, the auxiliary section being adapted to fold within the main section which carries it, and the other main section when the auxiliary section is 65 thus folded being adapted with said main section to inclose the auxiliary section, the auxiliary section, when the main sections are opened, being movable to occupy a position at right angles to the section which carries 70 it, the other main section having a slot at its free end which receives the auxiliary section when at right angles to the main section carrying it, the auxiliary section when in said right angular position being adapted to abut 75 against the back wall of said slot.

In testimony whereof I affix my signature in the presence of two witnesses.

HUBERT C. HART.
